The ornamental design for a parasol stand, as shown and described.

DESCRIPTION

FIG. 1 is a perspective view of the parasol stand of our invention;

FIG. 2 is a front/side view of the parasol stand;

FIG. 3 is a rear/opposite side view of the parasol stand;

FIG. 4 is a top plan view of the parasol stand;

FIG. 5 is a bottom view of the parasol stand; and,

FIG. 6 is a perspective view of the parasol stand with the rolling base of the parasol stand shown separated from a remainder of the parasol stand.

The evenly broken lines shown indicate portions of the parasol stand and form no part of the claimed design. The dash-dot-dash broken lines define the bounds of the claimed design and form no part thereof.
